UNITED STATES PATENT OFFICE.

JOSEPH DERK, OF PHILADELPHIA, PENNSYLVANIA, ASSIGNOR TO THE DERK MANUFACTURING COMPANY, OF PHILADELPHIA, PENNSYLVANIA, A CORPORATION OF PENNSYLVANIA.

DESIGN FOR A VALANCE FOR WINDOW DRAPERIES.

Application filed November 9, 1926. Serial No. 19,649. Term of patent 8½ years.

To all whom it may concern:

Be it known that I, JOSEPH DERK, a citizen of the United States, residing in the city and county of Philadelphia, State of Pennsylvania, have invented a new, original, and ornamental Design for Valance for Window Draperies, of which the following is a specification, reference being had to the accompanying drawing, forming part thereof.

The figure is a plan view of a valance for window draperies showing my new design.

I claim:—

The ornamental design for a valance for window draperies as shown.

JOSEPH DERK.
